CLAIM

The ornamental design for a slipper with panes as shown and described.

DESCRIPTION

FIG. 1 is a top view of a slipper with panes showing our new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a cross-section view thereof taken along line 7-7 of FIG. 1;

FIG. 8 is a cross-section view thereof taken along line 8-8 of FIG. 1;

FIG. 9 is a cross-section view thereof taken along line 9-9 of FIG. 1;

FIG. 10 is a cross-section view thereof taken along line 10-10 of FIG. 1;

FIG. 11 is a cross-section view thereof taken along line 11-11 of FIG. 1;

FIG. 12 is a cross-section view thereof taken along line 12-12 of FIG. 1;

FIG. 13 is a right side view in a condition of use showing an opened pane in the toe section of the slipper; and,

FIG. 14 is a left side view in the condition of use seen in FIG. 13.

The broken lines in the figure views depict portions of the slipper with panes that form no part of the claimed design. The broken lines showing the leg and foot in FIGS. 13 and 14 represent environmental structure that form no part of the claimed design.

1 Claim, 8 Drawing Sheets
